UNITED STATES PATENT OFFICE.

WILLIAM A. WOIWOD, OF GARNER, IOWA.

GATE-LATCH.

1,264,244.

Specification of Letters Patent. Patented Apr. 30, 1918.

Application filed February 16, 1918. Serial No. 217,610.

To all whom it may concern:

Be it known that I, WILLIAM A. WOIWOD, a citizen of the United States, residing at Garner, in the county of Hancock and State 5 of Iowa, have invented certain new and useful Improvements in Gate-Latches, of which the following is a specification, reference being had to the accompanying drawings.

This invention relates to certain improvements in gate latches and has relation more particularly to a device of this general character especially designed and adapted for use in connection with a substantially horizontally swinging gate and it is an object 5 of the invention to provide a novel and improved latch of this general character comprising a pair of vertically movable holding members normally maintained at the limit of their upward movement and which receive therebetween the forwardly directed extension or latch bar carried by the gate for holding the gate in closed position.

It is also an object of the invention to provide a novel and improved latch of this general character including vertically movable members together with means for protecting said members against the elements, and particularly ice and sleet so that the efficiency of the latch will not be impaired during the 10 winter season.

Another object of the invention is to provide a novel and improved latch comprising two vertically movable members between which the forwardly directed extension or latch bar of the gate is adapted to be seated and whereby said members may be readily depressed by a person at either side of the gate.

The invention consists in the details of 10 construction and in the combination and arrangement of the several parts of my improved gate latch whereby certain important advantages are attained and the device rendered simpler, less expensive and otherwise 5 more convenient and advantageous for use, as will be hereinafter more fully set forth.

The novel features of my invention will hereinafter be definitely claimed.

In order that my invention may be the 10 better understood, I will now proceed to describe the same with reference to the accompanying drawings, wherein:

Figure 1 is a view in front elevation of a gate latch constructed in accordance with 5 an embodiment of my invention in applied

position, the coacting extension or latch bar of the gate being shown in section;

Fig. 2 is a fragmentary view in side elevation illustrating my improved gate latch in applied position;

Fig. 3 is a longitudinal vertical sectional view taken through my improved gate latch as herein set forth; and

Fig. 4 is a sectional view taken substantially on the line 4—4 of Fig. 3.

As disclosed in the accompanying drawings L denotes a latch post having disposed transversely across its outer face a plate 1 having its upper and lower margins defined by the outstanding flanges 2 and 3. The 70 upper flange 3 serves as a roof or guard for the vertically movable latch members L to be hereinafter more particularly referred to and whereby said members L and their concomitant parts are effectively protected 75 against the elements and particularly ice and sleet.

Each of the latch members L is substantially in the form of an inverted L with the outer end portion of its stem 4 suitably engaged with a spring hinge 5 which is also suitably anchored to an end portion of the flange 2. The action of the spring hinge 5 serves to constantly urge the latch member upwardly. The foot 6 of the latch member 80 is directed through a transversely disposed slot 7 produced in the bottom flange 2 and the lower or free end of said foot 6 is provided with an inwardly directed lip or extension 8 adapted to contact with the end 85 surface of the bottom flange 2 whereby the upward movement of the latch L under the influence of the spring hinge 5 is positively limited.

The stems 4 of the latches are of such 90 length as to have the feet 6 of the latch members in predetermined spaced relation longitudinally of the flange 2 to afford a space or seat therebetween to receive a forwardly directed extension or latch bar 9 100 carried by the gate G. The gate G is hereinafter disclosed as of a type mounted for swinging movement in substantially a horizontal plane. As the gate G is swung toward the post P, the extension or bar 9 will ride over 105 one of the stems 4 of a latch member L to permit said extension or bar 9 to seat between the feet 6 of the latch members. When the bar has passed entirely along the stem 110 of the latch member, said member will be

automatically thrown upward under the influence of its coacting spring hinge 5 so that the gate is effectively held in closed position and against rebound.

Secured to the free end portions of the extensions or lips 8 are the comparatively short flexible members 10 preferably chains which are disposed downwardly in convergence and have their lower extremities engaged with the angular member or ring 11. Also secured to the ring 11 are the flexible members or chains 12 extending downwardly in divergence and suitably secured at their lower ends to the vertically swinging levers 14 engaged with the outer face of the post P in close proximity to the ground line and adjacent the opposite vertical margins thereof. The levers 14 are of a length to extend beyond the side faces of the post so that said extended levers may be readily depressed by a foot when it is desired to lower the latch members L to open the gate G.

As is particularly illustrated in the accompanying drawings, the inner end portion of each of the levels is pivotally engaged as at 15 with the outer face of the post and the flexible member or chain 12 coacting therewith is engaged with said lever at a point intermediate its pivotal connection 15 and its outer or extended extremity.

Each of the feet 6 of the latch members possesses sufficient inherent resiliency as to contact with the inner longitudinal marginal portion of the slot 7 so that the proper contact of the extension or lip 8 carried with the under surface of the flange 2 is assured. It is also to be noted that the extension or lip 8 is of a width slightly less than the width of the slot 7 so that the same may be readily passed therethrough when the various parts comprised in my improved latch are being assembled.

The hinges 5 as herein disclosed are of a leaf type and the lower leaf a thereof coacting with the lower flange 2 is detachably engaged with the flange 2 so that when desired the latch members L may be readily removed or applied. This detachable feature is of special importance in the winter season as it permits the removal of the latch members at the time of a snow storm as it may be possible that the snow would choke or otherwise interfere with the necessary movement of the members L.

From the foregoing description, it is thought to be obvious that a gate latch constructed in accordance with my invention is particularly well adapted for use by reason of the convenience and facility with which it may be assembled and operated and it will also be obvious that my invention is susceptible of some change without departing from the principles and spirit thereof and for this reason I do not wish

to be understood as limiting myself to the precise arrangement and formation of the several parts herein shown in carrying out my invention in practice except as herein-after claimed.

70

I claim:

1. A gate latch consisting of a plate adapted to be disposed transversely of a latch post or the like, the upper and lower longitudinal margins being provided with outstanding flanges, the lower flanges being provided with a pair of transversely disposed slots at substantially the center thereof, a pair of latch members each substantially in the form of an inverted L with the stem thereof outwardly directed, a spring hinge securing the outer end portion of the stem to the lower flange and serving to constantly urge said stem upwardly, the feet of the latch members being disposed through the opening in the lower flange and provided at its lower end with the inwardly directed lip arranged for contact with the bottom flange for limiting the upward movement of the latch member, and means engageable with the lips of both of the latch members for moving said members downwardly.

75

2. A gate latch consisting of a plate adapted to be disposed transversely of a latch post or the like, the upper and lower longitudinal margins being provided with outstanding flanges, the lower flange being provided with a pair of transversely disposed slots at substantially the center thereof, a pair of latch members each substantially in the form of an inverted L with the stem thereof outwardly directed, a spring hinge securing the outer end portion of the stem to the lower flange and serving to constantly urge said stem upwardly, the feet of the latch member being disposed through the opening in the lower flange and provided at its lower end with an inwardly directed lip arranged for contact with the bottom flange for limiting the upward movement of the latch member, a flexible member engaged with the lip, a coupling member coacting with both of said flexible members, and means engageable with said coupling member for imparting downward movement to the latch members.

80

3. In combination with a latch post, a plate disposed transversely of the post, and having its upper and lower margins provided with outstanding flanges, the lower flange being provided at substantially its center with a pair of transversely disposed slots, a pair of latch members, each of said latch members being substantially in the form of an inverted L and having the outer end portion of its stem outwardly directed and pivotally engaged with the lower flange, the stem of the latch member being disposed through an opening in the lower

flange, means coacting with the stems of the latch members for constantly urging the same upwardly, oppositely directed levers pivotally engaged with the lower portion of the latch post, flexible members engaged with the lower end portions of the feet of the latch members, a member with which said flexible members are engaged, and connections between the levers and the

member whereby downward movement of 10 either of the levers imparts downward movement to the latch members.

In testimony whereof I hereunto affix my signature in the presence of two witnesses.

WILLIAM A. WOIWOD.
